UNITED STATES PATENT OFFICE.

WILBUR F. OSBORNE, OF ANSONIA, CONNECTICUT, ASSIGNOR OF ONE-HALF
TO THE ANSONIA O. & C. COMPANY, OF SAME PLACE.

DESIGN FOR A SUSPENDER-END.

SPECIFICATION forming part of Design No. 26,728, dated March 9, 1897.

Application filed October 26, 1894. Serial No. 527,089. Term of patent 14 years.

To all whom it may concern:

Be it known that I, WILBUR F. OSBORNE, of Ansonia, in the county of New Haven and State of Connecticut, have invented a new 5 Design for Suspender-Ends; and I do hereby declare the following, when taken in connection with the accompanying drawings and the letters of reference marked thereon, to be a full, clear, and exact description of the same, 10 and which said drawings constitute part of this specification, and represent, in

Figure 1, a view in front elevation of a suspender-end containing my design; Fig. 2, a 15 broken edge view of a fragment of the braid containing my design and used in the production of the suspender-end shown by Fig. 1.

This invention relates to a design for a suspender-end; and the design consists in the configuration hereinafter described, and 20 shown in the accompanying illustrations.

My newly-designed suspender-end comprises a ring A, a suspension strap or piece B, and two members C C, each of which is made by doubling a strip of braid C' edgewise 25 upon itself and securing its adjacent edges together, except at the lower ends of the members, where the adjacent edges of the

braid are not secured together, but separated to form loops or buttonholes D D. The braid is composed of hard-twisted round cords 30 braided so that a "herring-bone" effect is produced in the longitudinal center of each braid by the angular arrangement of the central cords, which stand apart or are sufficiently separated from each other to produce, as aforesaid, a herring-bone effect. On the edges of 35 the braids the cords lie close together without intervening spaces and form long welt-like lines of compact braiding along each edge of the central longitudinal herring-bone 40 work. The cords employed being hard-twisted and round do not mash down, but retain their round form after being braided and give character and boldness to the effect.

I claim—

The design for a suspender-end as herein shown and described.

In testimony whereof I have signed this specification in the presence of two subscribing witnesses.

WILBUR F. OSBORNE.

Witnesses:

FRANKLIN R. JOHNSON,
WILLIAM HALSE.
